UNITED STATES PATENT OFFICE.

FORREST L. ELLISON, OF EXETER, NEW HAMPSHIRE.

TURNED SHOE.

Application filed January 27, 1923. Serial No. 615,193.

To all whom it may concern:

Be it known that I, FORREST L. ELLISON, a citizen of the United States, residing at Exeter, in the county of Rockingham and State of New Hampshire, have invented new and useful Improvements in Turned Shoes, of which the following is a specification.

This invention relates to a turned shoe, in which a welt is laid on the upper surface of the sole and united to the sole by an inside row of stitches passing through the inner edge portion of the welt, and the inturned edge portion of the upper is united to the welt by inclined stitches passing through the central portion of the welt, and inward and downward to the inner edge of the welt, said inclined stitches being interlocked with the said inside stitches, to form a secure union between the welt and sole, without entering the sole, so that the stitches uniting the upper to the welt are not exposed by the wearing away of the tread face of the sole.

I have found that a turned shoe constructed as above stated, is open to the objection that the outer edge portion of the welt is so far from the interlocked portions of the inclined and the inside stitches, that said outer edge portion is not closely confined against the outer edge portion of the sole, when the shoe is turned right side out, after the operation of securing the upper to the welt, which operation is performed while the shoe is turned inside out.

The object of the invention is to obviate this objection. I accomplish this object by additionally uniting the welt to the sole by a row of outside stitches passing through the outer edge portion of the welt into the marginal portion of the sole, said outside stitches being visible on the upper surface of the welt in the completed shoe.

Of the accompanying drawings forming a part of this specification,—

Figure 1 is a fragmentary sectional perspective view, showing the sole, the welt and the outside and inside stitches.

Figure 2 is a fragmentary perspective view, showing the upper united to the welt by the inclined stitches, the shoe being inside out.

Figure 3 is a view similar to Figure 2, showing the shoe turned right side out.

The same reference characters indicate the same parts in all the figures.

In the drawings, 12 represents the sole of a turned shoe, 13 represents a welt laid on

the upper surface of the sole, and united to the latter by a row of inside stitches 14, passing through the inner edge portion of the welt. These stitches may be laid in a channel, formed as usual, in the tread face of a leather sole, although when the sole is made of rubber, or like material such as neolin, which cannot be successfully channeled, the stitches 14 may be laid on the tread face.

The upper 15 has an inturned edge portion 15^a, which is laid on the upper surface of the welt, and is united to the latter by a row of inclined stitches 16, entering the welt about midway between the inner and outer edges of the latter, and extending to the lower inside corner of the welt, without entering the sole. Said inclined stitches intersect, and are interlocked with the inside stitches 14, so that a strong connection is provided between the upper and the sole by stitches which do not enter the sole, and are not exposed by wear of the tread face of the sole.

The inclined stitches 16 are formed while the upper and sole are inside out, the sole and welt being bent, as shown by Figure 2, to facilitate the formation of said stitches.

I am aware that I am not the first to propose making a turned shoe characterized as above stated. The described construction, while desirable for the reasons above mentioned, has not been successfully used heretofore, because of the distance between the inclined stitches 16, and the outer edge of the welt, this distance being such that the welt is free to move edgewise at its outer edge, so that when the shoe is turned right side out, there is a pronounced crack or crevice between the outer edges of the welt and sole.

I have overcome this defect and rendered the above described construction successful by additionally uniting the welt to the sole, by a row of outside stitches 18, passing through the welt between the outer edge of the latter and the upper, and visible when the shoe is completed, as shown by Figure 3. The stitches 18 may be formed either before or after the upper is stitched to the welt. They increase the strength and durability of the shoe, and improve its appearance.

I claim:

A turned shoe in which a welt is laid on the upper surface of the sole, and united to

the sole by an inside row of stitches passing through the inner edge portion of the welt, and the inturned edge portion of the upper is united to the welt by inclined stitches 5 passing through said inturned portion and through the central portion of the welt to the inner edge of the latter, and interlocked with said inside stitches, said shoe being charac-

terized by a row of outside stitches uniting the outer edge portion of the welt to the 10 sole, and holding down the outer edge portion of the welt upon the marginal portion of the sole.

In testimony whereof I have affixed my signature.

FORREST L. ELLISON.
